P. LOESSEL

GOVERNOR

Filed April 13, 1925

INVENTOR
P. Loessel

BY *L. Ledermann*
ATTORNEY

UNITED STATES PATENT OFFICE.

PAUL LOESSEL, OF ELIZABETH, NEW JERSEY.

GOVERNOR.

Application filed April 13, 1925. Serial No. 22,889.

The main object of this invention is to provide a novel type of governor for all types of power engines. This governor uses a pair of fulcrumed levers which describe an angular action and are driven by and drive crank shafts, one of the crank shafts transmitting rotational power to a load equalizer wheel.

Another object is to provide a governor having fulcrumed levers whose balance may be adjusted by a novel type of weight which may be moved lengthwise on the levers.

The above and other objects will become apparent in the description below, it which characters of reference refer to like-named parts in the drawing.

Referring briefly to the drawing, Figure 1 is a front elevational view of the device.

Figure 2 is a top plan view of the same. Figure 3 is a cross sectional view thru the balancing weight, showing the method of moving the same to various positions on the lever.

Referring in detail to the drawing, the numeral 10 indicates a base from which posts 11 and 12 extend vertically upward. These posts are integral with the base and are arranged in pairs, each pair having a space between them to provide room for insertion of blocks 13 in which levers 14 and 15 are rigidly mounted. The posts 11 and 12 have bushings 16 mounted in their upper ends, and in these bushings, studs 17 are rotatably mounted, said studs projecting from the sides of the blocks 13 into the bushings 16. Each of the levers 14 and 15 have the blocks 13 mounted rigidly thereon near one end in such manner that the levers are fulcrumed in the saddle formed by the blocks, the blocks being anchored on the levers near one of the ends. Below the short ends of the levers 14 and 15, a pair of arms 18 extend vertically upwardly and are spaced-apart from each other to provide a bearing at both ends of a shaft 19 having oppositely disposed crank arms 20 and 21 formed integral therewith. The crank arm 20 is connected to the lever 14 by a link 22 and the opposite crank arm 21 is connected to the other lever by a link 23. One end of the shaft 19 has a fly wheel 24 mounted thereon and adjacent this fly wheel, a pulley 25 is anchored which is driven by a band 26 connected to some rotating wheel or pulley of the engine or a machine to which this governor is attached. The upper edges of the

long ends of the levers 14 and 15 are provided with V-shaped teeth 27 and on the outer sides of these levers, a line of serrations 28 extends longitudinally on the face thereof. A hollow block 29 is slidably mounted on each of the long ends of the fulcrumed levers 14 and 15 and on one side of these levers, lugs 30 extend in which the spindle 31 of a roller 32 is rotatably anchored. The outer peripheries of these rollers are serrated and one half of the roller passes thru a slit 33 in the body of the hollow block and the serrated peripheries tangentially engage the serrations 28 on the levers 14 and 15. Mounted on the top of the hollow blocks 29 are resilient fingers 34 which project from one end of the blocks and these projecting ends are formed into tooth-like projections 35 which are adapted to engage with the portions 27 and releasably position the blocks in the desired position. A right angled resilient blade 36 is anchored on the side of the upper lugs 30 of the hollow blocks 29 and the ends of the blades are adapted to extend downwardly and engage the serrated periphery of the roller 32 to prevent the same from inadvertently moving when not desired. Beneath the ends of the long portions of the fulcrumed levers, a plate bracket 37 is mounted from which a pair of posts 38 and 39 extend upwardly. A crank shaft 40 having one crank 41 diametrically opposite the other crank 42 is rotatably mounted. These cranks 41 and 42 are connected to the long ends of the fulcrumed levers 14 and 15 by links 43 and 44 which are pivotally anchored to both the fulcrumed levers and the cranks 41 and 42. The end of the crank shaft 40 has a fly wheel 45 rigidly secured thereto.

The device is adapted to serve as a governor for any type of rotating or power machines. The pulley 25 is hitched to the machine which is to be governed by a belt 26. The shaft 19 is driven by the pulley and rotates the cranks 20 and 21 which in turn impart a reciprocating motion to the links 22 and 23. These links being pivoted to the short ends of the fulcrumed levers 14 and 15, arcuately swing the latter and rotate the crank shaft 40 whose cranks 41 and 42 are connected to the long ends of the fulcrumed levers 14 and 15 by the links 43 and 44. The balance of the fulcrumed levers may be adjusted thru shifting of the hollow blocks 29

thereon. These hollow blocks 29 are shifted longitudinally on the fulcrumed levers 14 and 15 by rotating the rollers 32 whose serrated peripheries engage in the lunar serrations 28 formed on the fulcrumed levers 14 and 15. As the hollow blocks are being moved on the fulcrumed levers, the tooth-like projection 35 on the resilient finger 34 rides over the teeth 27, and when the hollow block comes to rest, the tooth-like projections 35 releasably lock the hollow blocks in that position on the levers.

I claim:—

In a governor having fulcrumed levers, lever balancing means comprising blocks adapted to be adjusted longitudinally on said levers, said levers having a linear line

of serrations extending longitudinally thereon intermediate their width, said blocks comprising hollow members slidably mounted on the fulcrumed levers, rollers rotatably mounted in the sides of the blocks, the peripheries of said rollers being serrated, the serrated peripheries of the rollers engaging the serrations on the levers to move the hollow blocks longitudinally thereon, fingers mounted on said blocks, teeth on one edge of said fulcrumed levers, fingers on said blocks, one end of said fingers projecting from the blocks and engaging said teeth on the fulcrumed bar to releasably secure said hollow blocks in position on the lever.

In testimony whereof I affix my signature.
PAUL LOESSEL.
